Farnsworth Television and Radio Corporation,
a corporation of Delaware

Original application January 22, 1941, Serial No.
375,389. Divided and this application January
15, 1943, Serial No. 472,442

3 Claims. (Cl. 274—15)

This invention relates to an automatic phonograph, and more particularly to new and useful improvements in pickup arm control mechanisms. This application is a division of my copending application, Serial No. 375,389, filed January 22, 1941, now Patent No. 2,313,262, granted March 9, 1943.

The principal object of the present invention is to provide an improved mechanism for controlling the movement of the pickup arm used with the record-changing apparatus so that the stylus of the reproducer engages a record on the turntable with the least possible pressure.

In accordance with the present invention, there is provided a phonograph comprising a turntable, a pickup arm with a reproducer at one end thereof for cooperating with a record on the turntable, a supporting means for the pickup arm, cam means, and pickup arm control means. The pickup arm control means is associated with the cam means and is adapted to engage the pickup arm intermediate the reproducer and the supporting means for moving the reproducer into engagement with the outer groove of the record on the turntable.

For a better understanding of the invention, together with other and further objects thereof, reference is made to the following description taken in connection with the accompanying drawings, and its steps will be pointed out in the appended claims.

In the accompanying drawings:

Fig. 1 is a top plan view of a pickup arm in playing position upon a record;

Fig. 2 is an assembly view, partly in section, of the pickup arm moving mechanism;

Fig. 3 is a side elevation view of the pickup arm moving mechanism; and

Fig. 4 is a view taken on line 4—4, of Fig. 3, showing a cam and associated mechanism for controlling horizontal movement of the pickup arm.

Referring particularly to Figs. 1 and 3 of the drawings, the invention is illustrated as having a base plate 10. Disposed above the base plate 10 is a horizontally rotatable turntable 11 for supporting a record 12. The turntable may be driven by any suitable mechanism such, for example, as that shown and fully described in my copending application, identified hereinbefore.

Means for playing the record 12 comprises a reproducer 13 with a stylus 14 (Fig. 2) which cooperates with the record on the turntable 11. The reproducer 13 is supported at the free end of pickup arm 15, the other end of which is

5 mounted on the pedestal 16 so that it can pivot in a vertical plane on two points at different times and can be swung in a horizontal plane around the axis of the pedestal. The pedestal 16 is provided with a hollow rotatable shaft 18 in which a pin 19 is adapted to move vertically (Fig. 2). To the top of the shaft 18 is affixed 10 a plate 21 which is adapted to move over the top of the pedestal 16 with the least possible friction. To one end of the plate 21, a plate 22 is connected by means of a pin 23. Intermediate its ends, the plate 22 is provided with a bearing portion 25 which supports, by means of a pin 26, a bracket 27 fixedly secured to the pickup arm 15, as shown in Fig. 2. The pickup arm 15 is affixed to the bracket 27 so as to pivot on the bearing pin 26 when the stylus of the reproducer is in engagement with a record on the turntable. A suitable weight 30 is provided in the pivoted end 15 of the pickup arm 28 to maintain a predetermined stylus pressure on a record on the turntable.

20 The pickup arm 15 is raised and lowered with respect to a record on the turntable by means of pin 19 together with cam surface 33 on cam wheel 34. The cam wheel 34 is affixed to drive shaft 35 which may be driven through a mechanism shown and fully described in my copending application, identified hereinbefore. As 25 shown in Figs. 2 and 3, the portions 32 and 36 of cam surface 33 cooperate in raising and lowering the pin 19 and thereby in raising and lowering the plate 22. Screw 38 at the other end of the plate 22 engages the pickup arm 15 (Fig. 2) and raises it out of cooperative relationship with a record on the turntable.

30 After the pickup arm 15 has been raised, the cam wheel 34 has rotated to the position where an inclined portion 40 of a cam surface 41 engages a pin 42 fixed to a lever 43 which is connected to the lower end of the shaft 18 (Figs. 2 and 3) to rotate therewith. The continued rotation of the cam wheel 34 moves the pin 42 and therewith the lever 43 outwardly in a horizontal plane. After the inclined portion 40 of the cam surface 41 has moved past the pin 42, the lever 43 has positioned the pickup arm 15 beyond the edge of the record on the turntable 11, as shown in dotted lines in Fig. 1.

35 While the cam surface 41 is in engagement with the pin 42, a pin 46 is in engagement with a cam surface 47 (Fig. 3) of the cam wheel 34. The pin 46 is secured to the free end of a spring-biased lever 48 which is affixed to a rod 50, to 40 the upper end of which is affixed a lever 51 (Fig.

3. The rod 50 is mounted on the base plate 10 to move in a vertical direction. The contour of the cam surface 47 is shown in dotted and full lines in Fig. 3. Immediately after the pickup arm has been swung to its outermost position, the portion 53 of the cam surface 47 moves into engagement with the pin 46. This raises the pin 46, the rod 50 and the lever 51. The rod 50 is raised against the biasing action of spring 54. Immediately after the lever 51 is raised, the pin 48 moves off of the portion 36 of cam surface 33. This allows the pickup arm to come into engagement with a pin 55 affixed to the free end of the lever 51. During the time the pickup arm is being lowered into engagement with the pin 55 and for a short time thereafter, the cam surface 56 (Fig. 4) is in engagement with the pin 46 which prevents the pickup arm from moving inwardly. Immediately after a record has been placed on the turntable, the notch 58 in the cam surface 56 (Fig. 4) allows the pin 46 which is under the biasing action of a spring 60 (Fig. 4) to move so that it transmits inward movement to the pickup arm. One end of the spring 60 is anchored to the lever 48 and the other end is anchored to a pin 61 which may be affixed to the underside of the base plate 10. After the pin 46 is in engagement with the portion 58A of the notch 58, the pickup arm has been moved inwardly sufficiently far to position the stylus 14 of the reproducer 13 over the outer groove of a ten-inch record on the turntable.

If a twelve-inch record is on the turntable 11, the pickup arm 15 will be swung inwardly until a fiber roller 65 on the lever 51 engages the peripheral edge of the twelve-inch record. This engagement positions the stylus of the reproducer over the outer groove of a twelve-inch record.

As the cam wheel 34 continues to rotate, a portion 66 of cam surface 47 moves under the pin 46. This allows the spring 54 to force downwardly the rod 50 and therewith the levers 48 and 51. The downward movement of the lever 51 positions the stylus of the reproducer 13 into engagement with the outer groove of a record on the turntable. After the stylus is in engagement with the outer groove of the record on the turntable, the continued movement of the cam surface 47 allows the pin 46 to move into the notch 67 of the cam surface 47 (Fig. 3). This allows the levers 48 and 51 to be lowered still further. The further lowering of the lever 51 moves the pin 55 out of engagement with the pickup arm 15. After the pin 55 is out of engagement with the pickup arm 15, a portion 58B of the notch 58 moves into engagement with the pin 46. The continued movement of the cam wheel 34 causes the pin 46 and the arm 48 to move in a counterclockwise direction (Fig. 4) against the biasing action of the spring 60 to the position shown in Figs. 1 and 4. When the pin 46 and the lever 48 have been moved back to the latter position, the driving mechanism previously referred to for the record-changing apparatus is automatically shut off and reproduction of a record on the turntable is begun.

In operation, the pickup arm 15 moves inwardly toward the center of a record on the turntable 11 as the stylus 14 follows the playing grooves of the record. As the pickup arm 15 moves inwardly, the pin 42 likewise moves inwardly in a clockwise direction, (Figs. 2 and 4). When the stylus 14 reaches the innermost or tripping groove of a record, the mechanism is tripped in the manner fully described in the afore-

mentioned application, and the drive shaft 35 (Fig. 2) is rotated.

As the shaft 35 and cam wheel 34 begin to rotate, the portion 32 of the cam surface 33 (Fig. 3) engages and lifts the pin 19, whereby its upper end engages the under side of the plate 22 causing it to pivot on pin 23 and thereby move the screw 38 into engagement with the pickup arm 15 (Fig. 2). Immediately thereafter, the high point of the cam surface 33 moves under the pin 18, whereby the plate 22 is moved upwardly sufficiently far to lift the pickup arm 15 and the stylus 14 out of engagement with the record 12.

15 When the cam wheel 34 has rotated to such a position that the stylus 14 is lifted out of engagement with the record 12 (Fig. 2), the angular portion 40 of the cam surface 41 (Fig. 4) has moved into engagement with the pin 42 (Figs. 2 and 4). Continued rotation of the cam wheel 34 causes the pin 42 and the lever 43 to move outwardly in a counterclockwise direction (Figs. 2 and 4). By the time the pin 42 reaches the end of the angular portion 40, the lever 43 and therewith the pickup arm 15 is moved to the position wherein the pickup arm 15 is at its outermost position beyond the edge of the record on the turntable, as indicated by dotted lines in Fig. 1 of the drawings.

30 Immediately after the pickup arm has been moved to its outermost position, the cam wheel 34 rotates to such a position that the portion 53 of the cam surface 47 (Fig. 3) engages and moves the pin 46 and therewith the levers 48 and 51 vertically upward. The pin 19 then moves off of the cam portion 33 (Fig. 3) to lower the pickup arm 15 into engagement with the pin 55 of the lever 51 (Fig. 3).

Shortly after the record on the turntable has 40 been reversed or a new record has been moved into playing position on the turntable, the cam wheel 34 rotates to such a position that the pin 46 engages the notch 58 of the cam surface 56 (Fig. 4) to allow the coil spring 60 to move the levers 48 and 51 and therewith the pickup arm 15 inwardly. When the pin 46 engages the portion 58A of the notch 58, the pickup arm 15 is approximately over the outer groove of the record on the turntable.

50 Continued rotation of the cam wheel 34 causes the eccentric portion 66 of the cam surface 47 (Fig. 3) to engage the pin 46, allowing the pin 50 and the levers 48 and 51 gradually to lower the pickup arm and the stylus into engagement 55 with the outer groove of the record on the turntable. When the notch 67 moves under the pin 46, the spring 54 forces the lever 51 and pin 55 out of engagement with the pickup arm 15, whereupon the cam portion 58B engages and moves the pin 46 and therewith the levers 48 and 51 outwardly to the position shown in Fig. 1. Immediately thereafter, the driving mechanism for the cam wheel 34 is stopped and reproduction of the record on the turntable takes place.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A phonograph comprising a turntable, a

pickup arm including a reproducer for cooperating with a record on said turntable, supporting means for said pickup arm, elevating means operatively associated with said supporting means for lifting and lowering said pickup arm, rotatable means connected to said supporting means for moving said pickup arm outwardly from the center of a record on said turntable, cam means associated with said elevating means and said rotatable means for operating them in timed relation and a pickup arm control means operatively associated with said cam means and movable thereby to engage and support said pickup arm intermediate said reproducer and said supporting means when the pickup arm is being lowered by said elevating means for moving said pickup arm inwardly and downwardly into engagement with the outer groove of the record on said turntable.

2. A phonograph comprising a turntable, a pickup arm including a reproducer for cooperating with a record on said turntable, supporting means for said pickup arm, elevating means operatively associated with said supporting means for lifting and lowering said pickup arm, rotatable means connected to said supporting means for moving said pickup arm outwardly from the center of a record on said turntable, cam means associated with said elevating means and said rotatable means for operating them in timed relation, a pickup arm control means adapted to

engage and support said pickup arm intermediate said reproducer and said supporting means when the pickup arm is being lowered by said elevating means, and cam means operatively associated with said pickup arm control means for moving said pickup arm inwardly and downwardly into engagement with the outer groove of the record on said turntable.

3. A phonograph comprising a turntable, a pickup arm including a reproducer for cooperating with a record on said turntable, supporting means for said pickup arm, a vertically disposed pin operatively associated with said supporting means for lifting and lowering said pickup arm, rotatable means connected to said supporting means for moving said pickup arm outwardly from the center of a record on said turntable, cam means associated with said pin and said rotatable means for operating them in timed relation, a pickup arm control means adapted to engage and support said pickup arm intermediate said reproducer and said supporting means when the pickup arm is being lowered by said pin, cam means operatively associated with said pickup arm control means for moving said pickup arm control means inwardly and downwardly, and stop means on said pickup arm control means for engaging said record and guiding said reproducer into engagement with the outer groove of the record on said turntable.

JACKSON HARD PRESSLEY.
